UNITED STATES PATENT OFFICE

136,949

DESIGN FOR AN ELECTRIC FENCE POST

Ernest S. Cooke, Leawood, and Glenn E. Richards, Kansas City, Kans.

Application October 15, 1943, Serial No. 111,380

Term of patent 7 years

To all whom it may concern:

Be it known that we, Ernest S. Cooke, a citizen of the United States, residing at Leawood, in the county of Johnson and State of Kansas, and Glenn E. Richards, a citizen of the United States, residing at Kansas City, in the county of Johnson and State of Kansas, have invented a new, original, and ornamental Design for an Electric Fence Post, of which the following is a specification, reference being had to the accompanying drawing, forming a part thereof, in which:

Fig. 1 is a front elevation of an electric fence post, showing our new design.

Fig. 2 is a side elevation thereof.

We claim:

The ornamental design for an electric fence post, substantially as shown.

ERNEST S. COOKE.
GLENN E. RICHARDS.
